UNITED STATES PATENT OFFICE

JAMES E. BUSHNELL, OF NORTH PLAINFIELD, NEW JERSEY, ASSIGNOR TO RANSOME CONCRETE MACHINERY COMPANY, OF PLAINFIELD, NEW JERSEY, A CORPORATION OF NEW JERSEY

MATERIAL-CONTROL MECHANISM FOR CONCRETE MIXERS

Application filed February 23, 1928. Serial No. 256,208.

The present improvements relate in general to concrete mixing apparatus, and more particularly to the charging, timing and discharging operations attending the functioning of a mixer of this type.

In designing a mixing apparatus for preparing freshly mixed concrete in situ, it is essential that a rugged and sturdy construction be developed, as well as one which will 10 invariably produce a mixture having the proper proportions, consistency and predetermined mixing, under a plurality of conditions which may be encountered in the field. As is well known in the art, the requirements 15 of a most efficient mixture embrace, among others, a definite quantity of water and dry aggregates, the former thoroughly distributed throughout the latter, a predetermined mixing interval for these ingredients and 20 provision for preventing the withdrawal of the mass before the end of such interval.

The present improvements have as their primary object, among others, the provision of means meeting such requirements in an 25 improved manner whereby the charging of the ingredients into the mixer, the determining of the mixing interval, the discharge control from the mixer, as well as other operations in connection therewith are coordinated 30 and synchronized to produce an improved mixture. Other objects of the present improvements will be apparent to those skilled in the art.

While the operations attending the mixing 35 function are herein disclosed as being controlled by the movements of the discharge device for dry aggregates, it will be apparent that other forms, within the scope of this invention, will be apparent to those familiar in 40 the art. The accompanying drawings illustrate one embodiment, in which—

Fig. 1 is a front view of a batch hopper embodying a portion of the present improvements;

Fig. 2 is a side view of the structure illustrated in Fig. 1, some parts in section, others omitted for convenience of illustration;

Fig. 3 is a side elevation of a mixer embodying the present improvements, the liquid 50 supply means being omitted;

Fig. 4 is an end view, looking in the direction of the arrow in Fig. 3;

Fig. 5 is a view similar to Fig. 1 with liquid supply means omitted, taken on line 5—5 of Fig. 3.

The general organization of the various elements and mixer is illustrated in Fig. 3, wherein the mixer 8, rotated by suitable power means (not shown), is fixedly mounted on mixer frame 9, said mixer having a charging opening 10 and a discharging opening 11. Suitable blades or other means (not shown) are provided within the mixer 8 for cooperating to effect discharge of the mixer contents through opening 11, when a discharge chute or other mechanism (not shown) is inserted therethrough for transferring said contents to barrows, chutes or other distributing means. A batch hopper 12 for dry aggregates, cement, etc., is suitably mounted on the rear of frame 9, so that its discharge opening 13 is in alignment with charging opening 10 of the mixer, for transfer of the dry ingredients from the former to the latter. Conveniently positioned on the front 75 of frame 9 is a batch meter or batch timing device 14, suitably associated and operatively connected with the mixer and power means therefor, for predetermining the mixing interval or revolutions of mixer 8. The frame 80 9, also has mounted thereon control means 15 for the discharge mechanism (not shown) of the mixer. For convenience of illustration, certain parts have been omitted from Fig. 3, however referring to Figs. 1 and 2, the liquid 85 supply means 16 for the mixer is depicted, which is also conveniently mounted on frame 9 in position to transfer the necessary liquid from discharge pipe or spout 26 into opening 10.

Referring more particularly to Figs. 1 and 2, a discharge control mechanism for batch hopper 12 is provided in the form of a door 17 normally closing opening 13 therein. Said door is adapted for opening and closing by means of bell crank lever 18 pivoted for rocking movement at 19 on any convenient support 20. A door actuating bar 21, has one end pivoted to one end of lever 18, with the other end pivoted at 22 to door 17 in any de- 90 95 100

sired manner. Obviously rocking lever 18 in a counter clockwise direction will open door 17 and movement of said lever in the opposite direction will close said door. Said lever 18, bar 21 and door 17 comprise the discharge control mechanism for batch hopper 12, which may be manually actuated or operated by any other power source.

The liquid or water supply means 16 for mixer 8, is suitably positioned and connected with said discharge control mechanism for response to certain movements thereof. Said water supply means 16 comprises a three-way valve 23 having a main supply inlet 24, a conduit 25 leading to a measuring tank (not shown) and a discharge pipe 26 leading to the mixer opening 10. Although any suitable three-way valve may be employed, one of the rotary plug type is herein shown, having an operating mechanism connected thereto comprising an arm 27 fixed to the valve plug. Said arm is actuated by means of a rod or link 28, said link and arm being operatively connected to one another at their ends by a universal joint 29. As illustrated in Fig. 2, link 28 is suitably threaded along a greater portion thereof, to accommodate lock nuts 30 and a capped nut 31. A pipe spacer or cylinder 32 telescopes the threaded portion of link 28 between said nuts and suitable stamped washers 33 are interposed between each nut and the adjacent end of pipe 32.

Mounted on lever 18 is a laterally extending lug 34 having an aperture therein greater in cross section than pipe 32 and link 28. Said last named elements are normally disposed through said aperture so that lug 34 embraces same. Obviously, in operation, said lug has freedom of movement (along pipe 32 and link 28) between the washers and lock bolts. The lug 34 is also provided with a slot extending from the aforementioned aperture through the edge of the lug whereby link 28 may be disengaged therefrom by grasping the handle of capped nut 31 for manual operation of the valve independent of lug 34 and lever 18. Additional water may thus be applied to the drum, if desired. Suitable releasable locking means bridges said slot for normally maintaining link 28 and lug 34 in co-operative relation.

The operation of the foregoing structure is as follows:—The door 17 of the batch hopper being closed, the parts are in the position illustrated in Figs. 1 and 2. At this time the valve 23 permits communication between supply 24 and conduit 25 to the water measuring tank, but closes the inlet to pipe 26 from conduit 25. The proper quantity of aggregates, cement, etc., having been placed in hopper 12, the lever 18 is rocked to the left in Fig. 1, the door 17 raising accordingly and initiating discharge from the hopper to mixer 8. As lever 18 ascends, carrying lug 34, the latter passes along link 28, from lower washer 33

to upper washer 33, without imparting movement thereto. So far, door 17 has been partially opened, permitting a limited discharge from hopper 12, no water however being turned on. Upon further rocking of said lever 18, lug 34 contacting upper washer 33, pulls link 28 upward, actuating valve 23 and fully opening door 17. In this operation, the three-way valve 23, closes communication from 24 to 25 and establishes communication 75 between the measuring tank (not shown) and the mixer 8, by way of conduits 25 and 26. The nuts 30, 31 and their washers are adjustable along link 28, said nuts being set and all other parts so proportioned that when the door 17 is fully opened, the water valve 23 is fully open to pass water from the tank to the mixing drum 8. The sequence of operation is reversed upon rocking lever 18 in a clockwise direction. It is thus seen that actuation of the door 17 functions, during the latter portion of its opening movement, to open the water supply means, a portion of the measured contents of the hopper 12 preceding the initial discharge of the measured quantity of water from the tank. Admitting a small portion of the dry ingredients, followed by simultaneous admission of the remaining dry and wet ingredients promotes efficient comixing in the drum. 95

Referring again to Fig. 3, a rock shaft 35 is suitably supported adjacent the top of frame 9, the end adjacent the batch hopper 12, having a radially extending dog 36 keyed thereto, the other end of said shaft 35 being operatively connected with the batch meter 14 for setting same. Bar 21 (Fig. 5) has a plate 37 adjustably mounted thereon, said plate provided with a laterally extending roller or bearing surface 38. As illustrated, said plate 37 is disposed on bar 21, so that roller 38 is in alignment with dog 36 of rock shaft 35, all upward movement of said bar functioning to rock said shaft. 100

The discharge control mechanism 15 for the mixer may be of any suitable form, that illustrated in Fig. 4 comprising a lateral spring controlled bar actuated by a handle 39. By raising the latter, discharge of said mixer by means of a chute or other mechanism is incepted. In order to prevent actuation of said means 15, before the predetermined mixing interval has transpired, locking means are provided therefor operatively connected with the batch meter 14 and rock shaft 35. In Figs. 3 and 4 this means is shown in locked position and comprises a bail 40 embracing handle 39 and keyed to pivot bar 41 for rocking to and from said handle. Said bail is provided with any suitable energized means, such as weight 42, for normally holding bail 40 in unlocked position. Keyed to pivot 41 is lever 43, diverging from the plane of said bail, the free end of said lever being pivotally connected to one 110 115 120 125 130

end of link 44. The other end of said link is operatively connected with the batch meter 14 and rock shaft 35 as hereinafter set forth. The bail 40 is held in locking position (Figs. 3 and 4) by the batch meter mechanism, which latter, after the predetermined mixing interval releases link 44, weight 42 then dropping and removing bail 40 from over handle 39.

10 The operation of the organization taken in connection with that previously described is as follows: Upon operation of the discharge control mechanism for the hopper 12, door 17 begins to open by the raising of bar 21. 15 Simultaneously plate 37 on bar 21, rocks dog 36, which in turn rotates shaft 35, said shaft, being connected to the batch meter 14 and locking mechanism, functions to set said meter and also move bail 40 to locking position 20 against the urge of weight 42. Setting of said meter results in holding said bail over handle 39 (thereby disabling same) until the mixing interval has transpired. After which said meter releases link 44, allowing weight 25 42 to withdraw bail 40 and simultaneously restore shaft 35 and dog 36 to their original position.

It is apparent that actuation of lever 18, results in discharge of the hopper contents and 30 water to the mixer, in the manner previously set forth, sets the batch meter and disables the discharge control mechanism of the mixer. While the meter controls the mixing in drum 8, and also locks the discharge control means, 35 the lever 18 may be restored to its original position, closing hopper door 17, closing pipe 26 and opening supply 24 to the measuring tank. By the time another batch is placed in hopper 12 and the water tank supplied with 40 water, the batch meter has released bail 40, permitting actuation of discharge means 15, while the batch meter mechanism or the weight 42 (through 43, 44, 14 and 35) has restored dog 36 to position for subsequent operation by plate 37 when an additional batch 45 is discharged to the mixing drum.

As evident from the foregoing description, the liquid supply means is delayed in its operation until a portion of the dry ingredients 50 have been supplied to the mixer 8, initial opening movement of door 17 however causes meter 14 to be set, and the mixer discharge means to be initially disabled. As above described the water supply means responds to 55 the latter portion of the opening movement of door 17 while bail 40 is fully brought over handle 39 and held there by meter 14, as set forth, thus completing the disabling operation initiated by the first opening movements of said door.

The present improvements as co-ordinated and synchronized promote a more thorough mixture of the mass and insure against premature discharge from the mixing drum, the 60 cooperating elements of the entire organiza-

tion contributing to produce an improved mass when withdrawn from the mixer.

Various modifications within the scope of the present improvements will be apparent to those skilled in the art. 70

What I claim is:

1. In apparatus of the character described the combination of a mixer, adapted to be charged and discharged, a plurality of charging devices therefor, a common positively operating means for said devices, a batch meter associated with said mixer and operating means, and means associated with said meter for preventing premature discharge of 75 said mixer.

2. In a mixing machine, the combination of a mixing drum, a batch hopper adapted to discharge its contents into said drum, a liquid supply means for said drum, a batch meter means for said drum, discharge control mechanism for said drum, disabling means therefor, and operative connections between said hopper and means, said connections comprising members directly connected to said batch meter means and disabling means and members 80 engageable with said liquid supply means after predetermined movement of said first named members whereby movement of said connections causing a limited discharge of said hopper actuates said batch meter means 95 and said disabling means and further movement causing a greater discharge actuates all said means.

3. In a mixing machine, the combination of a mixing drum, a batch hopper having a door 100 controlling discharge thereof to said drum, a liquid supply means for said drum, control means therefor responsive under predetermined conditions to said door movements, a batch meter for said drum, a discharge control means for said drum, disabling means for 105 said last named means, said door, batch meter and disabling means being operatively connected whereby said meter and disabling means are responsive to opening movement of 110 said door.

4. A charging and mixing device comprising a rotary drum, having charging and discharging openings, a batch hopper having a 115 normally closed door controlling discharge thereof into said mixer, operating means for said door, a liquid supply means for said mixer having a normally closed valve, delayed action operating means for said valve connected to said first named means, a batch meter associated with said drum, normally inactive mechanism operatively connected with said meter for preventing untimely discharge of said drum, and means responsive to the 120 opening movement of said door operating means for setting said meter and last named mechanism.

5. An apparatus as set forth in preceding claim 4, including means for restoring said 130

- last named mechanism to inactive position after a predetermined interval.
6. In a charging device for mixing apparatus the combination of a batch hopper having 5 charging and discharging openings, a closure for said discharge opening, a normally closed liquid supply means having an outlet adjacent the discharge area of said hopper and means associated with said closure and responsive to partial opening movement thereof, for 10 opening said supply means.
7. In a charging device for mixing apparatus the combination of a batch hopper having charging and discharging openings, a closure 15 for said discharge opening, a normally closed liquid supply means having an outlet adjacent the discharge area of said hopper and delayed action mechanism connecting said closure and supply means, all so constructed and arranged 20 that said supply means is opened and closed only by complete opening and closing of said closure.
8. In a charging device for mixing apparatus, the combination with a mixer, of a normally closed discharge hopper and liquid supply means adapted to discharge into said mixer, and means for successively opening 25 said hopper and liquid supply means and similarly closing same.
9. A charging device for mixing devices comprising a batch hopper having charging and discharging openings, a liquid supply means having an outlet adjacent said discharge opening, a door normally closing said discharge opening, having an operating arm, a valve normally closing said outlet having an actuating arm and means operatively connecting said arms and permitting limited relative movement thereof.
10. A charging device for mixing devices comprising a batch hopper having charging and discharging openings, a liquid supply means having an outlet adjacent said discharge opening, a door normally closing said discharge opening, having an operating arm, a valve normally closing said outlet having an actuating arm, spaced contacts mounted on 45 said last named arm and a lug on said first named arm, positioned for free movement between said contacts.
11. In apparatus of the character described, the combination of a mixer having charging and discharging openings, a charging device for said mixer having control means therefor, a batch meter associated with said mixer for predetermining the mixing period, mechanism for controlling discharge of said mixer, and operative connections between said control means, meter and mechanism.
12. In apparatus of the character described, the combination of a mixer, a batch hopper and batch meter associated therewith, discharge control means for said hopper operatively connected with said meter for setting 60 the latter and mechanism initially operable by said means and subsequently by said meter for controlling discharge of said mixer.
13. A charging and mixing apparatus comprising a rotary drum, a batch hopper having means for controlling discharge thereof to 70 said drum, means associated with said mixer for predetermining the mixing interval, locking means for preventing discharge of said drum associated with said means, mechanism actuated by opening movement of said first 75 named means for setting said other means and means for automatically unlocking said locking means at the end of the mixing interval.
14. A charging and mixing apparatus comprising a mixer, a batch hopper for charging 80 said mixer having a door, a rock shaft responsive to opening movement of said door, a batch meter for said mixer for predetermining the mixing interval, adapted to be set by said shaft during said opening movement, a lever for causing discharge of said mixer, a lock for said lever operatively connected with said meter and rock shaft, energized means associated with said lock, all so constructed and arranged that opening movement of said 85 door sets said meter and lock for the mixing interval, said elements thereafter being restored to normal position by said energized means.
15. A charging device for mixers comprising a batch hopper having charging and discharging openings, a liquid supply means having an outlet adjacent said discharge opening, a door normally closing said discharge opening, having an operating arm, a valve normally closing said outlet having an actuating arm, means operatively connecting 95 said arms and permitting limited relative movement thereof, and releasable means for disconnecting said arms.
16. A mixing device comprising a mixing drum adapted to be charged and discharged, a fixed hopper for charging said drum, a batch meter associated with said drum for determining the mixing interval and means 100 associated with said hopper and batch meter for preventing premature discharge of said drum.
17. A mixing device comprising a mixing drum adapted to be charged and discharged, 115 a fixed hopper for charging said drum, liquid supply means for said drum, a batch meter associated with said drum for determining the mixing interval and means associated with said hopper, batch meter and liquid supply 120 means for preventing premature discharge of said drum.
18. In a charging device for mixing apparatus the combination of a batch hopper having charging and discharging openings, a closure for said discharge opening, liquid supply means having an outlet adjacent the discharge area of said hopper and actuating mechanism for opening and closing said closure and means.

19. A mixing device comprising a mixing drum adapted to be charged and discharged, a hopper having an opening for charging said drum, a closure for said opening, liquid supply means for said drum, and interconnected mechanism for opening and closing said closure and means.

Witness my hand this 31st day of January, 1928, at Dunellen, New Jersey.
